(57)

CLAIM

The ornamental design for a playback device with icon, as shown and described.

DESCRIPTION

FIG. 1 shows a side view of a first embodiment of a playback device with icon.

FIG. 2 shows a perspective view thereof.

FIG. 3 shows a perspective view of a second embodiment of a playback device with icon; and,

FIG. 4 a rear view thereof.

The broken lines illustrate portions of the playback device that form no part of the claimed design.
